C. A. Snow & Co.

Inventor

UNITED STATES PATENT OFFICE.

ELBRIDGE G. WEST, OF CANANDAIGUA, NEW YORK, ASSIGNOR OF ONE-HALF TO ALASCO C. ROBISON, OF SAME PLACE.

CONDUCTOR CUT-OFF.

SPECIFICATION forming part of Letters Patent No. 445,516, dated January 27, 1891.

Application filed August 8, 1890. Serial No. 361,481. (No model.)

To all whom it may concern:

Be it known that I, ELBRIDGE G. WEST, a citizen of the United States, residing at Canandaigua, in the county of Ontario and State of New York, have invented a new and useful 5 Conductor Cut-Off, of which the following is a specification.

This invention relates to improvements in cut-offs.

10 The object of the present invention is to provide a simple and inexpensive attachment for rain-spouts and other conduits adapted to be readily operated and capable of shutting off the flow of rain-water to a cistern or reservoir.

The invention consists in the construction and novel combination and arrangement of parts hereinafter fully described, illustrated 20 in the accompanying drawings, and pointed out in the claims hereto appended.

In the drawings, Figure 1 is a side elevation of a portion of a rain-spout provided with a cut-off constructed in accordance with this invention, the cut-off being swung down 25 and not in use. Fig. 2 is a central longitudinal sectional view, the cut-off being shown in operative position. Fig. 3 is a sectional view to show the flanges on the cut-off.

Referring to the accompanying drawings, 1 30 designates a rain-spout provided at its lower end with a sliding section 2, capable of longitudinal movement on the rain-spout or supply-pipe 1, and has its lower end 3 reduced slightly and adapted to fit in the end 4 of a cistern-pipe 5 to form a continuous conduit

35 to a cistern to permit the flow of rain-water therein, and is adapted to be withdrawn from the cistern-pipe and engage one arm 6 of an elbow 7, which is hinged to the cistern-pipe.

40 The elbow is hinged to the pipe 5, and is adapted to be swung on the hinge 8 to bring its arm 6 to a vertical position and in alignment with the rain-spout to receive the reduced end 3 of the sliding section 2 to form

45 a cut-off for the rain-spout and direct water through the horizontal arm 9 of the elbow and prevent it passing through the cistern-pipe to the cistern or reservoir. The upper end 4 of the cistern-pipe 5 has its edge curved

50 and provided with extensions 10, which form a seat for the arm 9 of the elbow when the said arm 9 is in a horizontal position and the

cut-off is in operation, and the said arm 9 is provided with curved flanges 11, which are arranged upon opposite sides of the arm and 55 form deflectors to shed water and prevent any dripping from the rain-spout or supply-pipe entering the cistern-pipe when the cut-off is in use, and in winter the flanges prevent ice forming around the seat and freezing 60 the parts.

It will be seen that the cut-off is exceedingly simple and inexpensive in construction, and is adapted to be readily applied to any rain-spout and is effective in its operation, and there is no liability of its becoming 65 injured and useless. The cistern-pipe is arranged but a short distance below the rain-spout, and the movement of the sliding section 2 to bring its reduced end into engagement with either the elbow or the cistern-pipe 70 is limited.

From the foregoing description and the accompanying drawings the construction, operation, and advantages of the invention will 75 readily be understood.

What I claim is—

1. In a cut-off, the combination, with the supporting-pipe having a sliding section, of the cistern-pipe having its upper end provided with curved edges forming a seat, and the angle-elbow composed of straight sections, one of the sections being hinged intermediate its ends to one side of the seat, whereby the elbow is adapted to rest on the seat and 80 close the top of the cistern-pipe, substantially 85 as described.

2. In a cut-off, the combination of the cistern-pipe having its upper end provided with a seat, the elbow hinged to the cistern-pipe 90 and adapted to rest in the seat and having flanges 11, and the supply-pipe having the sliding section adapted to engage either the elbow or the upper end of the cistern-pipe, substantially as and for the purpose described. 95

In testimony that I claim the foregoing as my own I have hereto affixed my signature in presence of two witnesses.

ELBRIDGE G. WEST.
